STEAM-TRAP.

1,285,771.

Specification of Letters Patent. Patented Nov. 26, 1918.

Application filed January 31, 1917. Serial No. 145,583.

To all whom it may concern:

Be it known that we, LOUIS R. MERTENS and GOTTLÖB BINDER, citizens of the United States, residing at Philadelphia, county of Philadelphia, and State of Pennsylvania, have invented a new and useful Improvement 5 in Steam-Traps, of which the following is a full, clear, and exact description, reference being had to the accompanying drawings, which form a part of this specification.

Our invention relates to that type of trap designed for the purpose of collecting the condensation of high and low pressure exhaust 15 mains or other high or low pressure drains. The object of our invention is to provide a trap so constructed that, upon the water of condensation reaching a predetermined level, the trap will be automatically cleared with a minimum pressure of steam 20 by means of a steam valve so constructed as to positively remain open or closed, during the clearing or filling of the trap, independently of the steam pressure in the trap. A further object of our invention is to provide 25 means controlled by the steam valve to open a valve permitting the clearing of the trap, so arranged that the valve need not be balanced or compensated, but may be of the standard disk type. Our invention also contemplates such an arrangement of the actuating mechanism that the exhaust steam used in actuating the valve, when released, 30 will be prevented from escaping direct to the atmosphere and immediately condensing, but will be distributed over a comparatively large heated surface and allowed to dissipate gradually. Another object of the invention is to provide means to hold open 35 the exhaust valve to allow steam to be blown through the trap.

A preferred embodiment of our invention is shown in the accompanying drawings wherein:—

Figure 1 is a side view of the trap partly in section.

Fig. 2 is a rear view, partly in section, showing in detail a portion of the mechanism for automatically operating the water discharge valve.

Fig. 3 is a plan view of the supporting plate for the exhaust valve lever arrangement taken on line 3—3 of Fig. 1.

a is a casing of cylindrical form and provided with the flange *b*. Near the top of the 55 casing is the inlet port *c* having opposite to it the deflector *y* extending downwardly to a point near the bottom of the casing. Near the bottom on the opposite side of the casing is the exhaust port *d*. The cover *e*, 60 having the flange *f* and provided with the recess *g*, is suitably fastened to the casing. Fastened to the under side of the cover and extending downwardly into the casing is the hanger *h*. Extending through the cover adjacent to the hanger is the needle valve *i*, 65 having the adjustable stem *j*. Pivoted to the hanger *h* by the pin *k* is the lever *l* engaging at one end the valve stem and at its opposite end pivoted to the link *n*. Below 70 the lever *l* and pivoted to the opposite side of the hanger is the bifurcated lever *p* pivoted at *o* and also to the lower end of the link *n* and having the counterweight *r* on its opposite end. The lever *l* and the cross 75 member *s* of the hanger are provided with holes at their centers, through which the stem *t* of the valve float *u* extends. At the top of the stem *t* is adjustably fastened the stop *v*, and spaced below the stop *v* is adjustably fastened the stop *w*. The stem *t* is adapted to move up and down vertically 80 through the holes in the lever and hanger a predetermined distance fixed by the stops *v* and *w*.

The weight of the lever *l*, link *n* and the part of counterweight lever *p* between its pivot and the link *n*, tends to close the valve and hold it closed. This weight overbalances the effective weight of the heavy end 90 *r* of the counterweight lever when the latter is raised, as shown in full lines in Fig. 1; but when the lever *l* is lifted the heavy end of the lever is swung toward a horizontal position, whereat its effective weight overbalances the weight of the other parts of the valve control mechanism. Thus the weight of the parts *l*, *n*, *p*, of the valve control mechanism is so distributed and counterbalanced relatively to the pivots *k* and *o* that 100 (eliminating friction) said mechanism tends to move of its own weight into either the full line position or the dotted line position shown in Fig. 1 when it is moved by the float toward such position beyond an intermediate dead center at which said mechanism

is balanced on its pivots. Hence the valve-closing and valve-opening movements are partly effected by the float and are partly automatic and the valve control mechanism 5 maintains the valve both in open and closed positions while the float is moving between its upper and lower positions. It will be understood, however, that the friction of the parts of the valve control mechanism may 10 be such that a movement beyond its dead center will be required before it acts automatically to complete its movement; and if the friction is considerable, the movement in one or both directions may be almost, or 15 quite, positive. Even under these conditions, however, the valve control mechanism will necessarily remain in either of the extreme positions to which it is shifted until it is positively moved away therefrom by 20 the float.

To the cover *e* is fastened the cylinder *z* centered over the needle valve *i* having a trough-shaped base formed by the annular flange *x*. Within the cylinder is the piston 25 2, the head of which extends beyond the outer walls of the cylinder, and from which the annular flange 4 extends downwardly below the top of the flange *x*. The base is provided with the horizontal aperture 5 30 which extends into the cylinder; and beneath the plate 3 is the aperture 6 which connects with the aperture 5. A screw 7 extends into the aperture 5, whereby the escape of steam from the cylinder may be regulated.

To the top of the casing is suitably fastened the bracket 8 and the upright 9 having at its upper end the stop 10 and having pivoted to it the dog catch 11. The lever 12 is pivoted to the bracket at one end and 40 connected to the piston by means of the link 14 having a socket bearing in the piston head and pivoted to the lever 12. To the lever 12 is pivoted the rod 17 which is pivoted at one end to the stem 19 of a plunger 45 valve 20 suitably positioned at the exhaust port *d*. Passing through a suitable aperture in the base of the bracket 8 and also pivoted to the lever 12 is a rod 22, having about its lower portion the coil spring 23 held under 50 tension between the base of the bracket and the adjustable stop 24.

In practice, the inlet port *c* of the trap is connected to a steam exhaust main or drain. Steam and water of condensation pass 55 through the inlet port, striking the deflector and collecting at the bottom of the casing. As the water of condensation begins to collect in the trap, the parts are in the positions shown in full lines in Fig. 1. It will be observed that the lever 12 is in its downward position, and that the discharge valve is closed. As the level of the water in the trap rises, the float *u* rises, raising the stem *t* and moving the stop *w* toward the lever *l*. When 60 the water level has risen to a point where

it has been predetermined to clear the trap, the stop *w* contacts with the lever *l* and pushes it toward the position shown in dotted lines of Fig. 1. After the valve control mechanism is moved beyond its dead center 70 the counterweight *r* falls, moving the lever *l* to the position shown in dotted lines. The displacement of the lever *l* pulls the needle valve *i* open. Steam immediately passes through the needle valve into the cylinder *z*, 75 causing the piston 2 to rise. The movement of the piston is transmitted to the lever 12, causing it to assume the position shown in dotted lines in Fig. 1, where it contacts with the stop 10. The upward movement of the lever 12 is transmitted to the valve stem 19 through the rod 17, causing the valve stem to rise, opening the valve. The raising of the lever 12 causes the spring 23 to be compressed. 80

The water of condensation is now blown out of the trap, through the water discharge valve, by the steam pressure in the trap. As the water level lowers, the float sinks, and the stop *w* leaves the lever *l*, while the stop *v* approaches it. The counterweight now acts to keep the lever *l* in raised position and the needle valve *i* open, until the stop *v* contacts with and presses the lever back toward the position shown in full lines of Fig. 1, 90 lifting the counterweight until after the mechanism moves beyond its dead center and the counterweight raised to its former position, where it acts to keep the lever *l* in lowered position and the needle valve closed. 95 When the needle valve closes, the steam left in the cylinder *z* escapes through apertures 5 and 6 into the base, where it is laterally diverted by the plate 3 and distributed over the heated surface of the trough which prevents its condensation and allows it to dissipate gradually. The spring 23 at the same time acts to bring the lever 12 back to full line position and close the water discharge valve. Any leakage of steam through the piston while in its raised position is diverted downwardly into the trough by the annular flange 4, where it is allowed to evaporate. During the time that the needle valve is open, steam escapes from the cylinder 100 through the apertures 5 and 6, but in such small amounts as not to affect the working of the piston. The amount which escapes may be regulated by the screw 7. 105

If it is desired for any reason to maintain the exhaust valve open after the trap has been cleared, the lever 12 may be latched in its upper position by means of the dog catch 11.

Having now fully described our invention, 125 what we desire to claim and protect by Letters Patent is:

1. In a steam trap, the combination with a tank having an inlet and an outlet, of a discharge valve controlling said outlet, lever 130

mechanism movable into two positions and so counterbalanced as to remain in either position to which it is moved until positively shifted away therefrom, a float in the 5 tank movable independently of said lever mechanism for the greater part of its movement up or down but adapted, as it moves toward its upper or lower limit of movement, to effect a shift of said lever mechanism from one or the other of its said positions toward the opposite position, a cylinder, a piston therein connected with the discharge valve and controlling its operation, a steam valve controlling the admission of 10 steam to said cylinder, and means operable by the lever mechanism to operate the steam valve.

2. In a steam trap, the combination with a tank having an inlet and an outlet, of a 20 discharge valve controlling said outlet, lever mechanism movable into two positions and so counterbalanced as to remain in either position to which it is moved until positively shifted away therefrom, a float in the tank 25 adapted, as it moves toward its upper or lower limit of movement, to effect a shift of said lever mechanism from one or the other of its said positions toward the opposite position, a cylinder positioned above the 30 tank, a piston in said cylinder, a rod connected with the discharge valve, a pivoted lever connected with said rod and plunger, a steam valve controlling the admission of steam to said cylinder, and means operable 35 by the counterbalanced mechanism to operate the steam valve.

3. In a steam trap, the combination with a tank having an inlet and an outlet, of a discharge valve controlling said outlet, 40 counterbalanced lever mechanism comprising a pivoted lever, a link connected thereto and a pivoted counterweight connected to the link and tending to hold itself and the link and lever in one or another of two positions, a float in the tank adapted, as it approaches one or the other of its extreme vertical positions, to operate said lever and thereby shift it, the link and the pivoted counterweight away from one or the other 45 of said positions, and means operable by said counterbalanced lever mechanism to control the operation of the discharge valve.

4. A steam trap comprising a tank having an inlet and an outlet, a discharge valve controlling the outlet, a steam valve, a float in the tank controlling the operation of the steam valve, a piston and cylinder connected with the steam valve, connections between the piston and cylinder and the discharge 55 valve, a relief port in the cylinder, and means to throttle said port.

5. A steam trap comprising a tank having an inlet and an outlet, a discharge valve controlling the outlet, a steam valve, a float in 60 the tank controlling the operation of the

steam valve, a piston and cylinder connected with the steam valve, connections between the piston and cylinder and the discharge valve, a relief port in the cylinder, and a trough around the base of the cylinder and 70 with which said relief port communicates.

6. A steam trap comprising a tank having an inlet and an outlet, a discharge valve controlling the outlet, a steam valve, a float in the tank controlling the operation of the 75 steam valve, a piston and cylinder connected with the steam valve, connections between the piston and cylinder and the discharge valve, a relief port in the cylinder, a trough around the base of the cylinder and with 80 which the relief port communicates, and a member above the relief port and adapted to divert laterally into said trough steam escaping from the relief port.

7. A steam trap comprising a tank having 85 an inlet and an outlet, a discharge valve controlling the outlet, a steam valve, a float in the tank controlling the operation of the steam valve, a cylinder connected with the steam valve, a piston in the cylinder whose 90 head extends beyond the walls thereof and a downwardly extending annular flange depending from the piston head and surrounding and spaced from the cylinder.

8. A steam trap comprising a tank adapted 95 for connection with a steam pipe, a steam valve, a cylinder connected to said steam valve, a piston adapted to travel in said cylinder and having its head extending beyond the walls thereof, a trough about the base 100 of said cylinder, a port connecting said trough with the inside of said cylinder, and a downwardly extending flange about the head of said piston.

9. A steam trap comprising a tank having 105 an inlet and an outlet, a discharge valve controlling the outlet, a steam valve, a float in the tank controlling the operation of the steam valve, a cylinder connected with the steam valve, a piston in the cylinder whose 110 head extends beyond the walls thereof and a downwardly extending annular flange depending from the piston head and surrounding and spaced from the cylinder, and a trough surrounding the cylinder 115 whose annular wall extends outside of, and above, the lower edge of said flange.

10. A steam trap comprising a tank having an inlet and an outlet, a discharge valve controlling the outlet, a steam valve, a float 120 in the tank controlling the operation of the steam valve, a piston and cylinder connected with the steam valve, connections between the piston and cylinder and the discharge valve, a tension device tending to move the 125 discharge valve into closed position and acting in opposition to the steam actuated piston, and manually operable means to hold said connections from being actuated by the tension device.

11. A steam trap comprising a tank adapted for connection with a steam pipe, a steam valve, a cylinder connected to said steam valve, a piston adapted to travel in said cylinder and having its head extending beyond the walls thereof, a trough about the base of said cylinder, a port connecting said trough with the inside of said cylinder, and

adjustable means adapted to throttle said port.

In testimony of which invention, we have hereunto set our hands, at Philadelphia, on this 30th day of January, 1917.

10
